Primary Examiner — Ricky Pham(74) *Attorney, Agent, or Firm* — Brinks Gilson & Lione; John C. Freeman(57) **CLAIM**

The ornamental design for a blender, as shown and described.

DESCRIPTION

FIG. 1 is a front perspective view of a blender according to the present invention;

FIG. 2 is a front view thereof;

FIG. 3 is a rear view thereof;

FIG. 4 is a right side view thereof; and,

FIG. 5 is a left side view thereof.

(Continued)

The ornamental design which is claimed is shown in solid lines in the drawings. The broken lines showing of portions of the article form no part of the claimed design.

1 Claim, 5 Drawing Sheets
